UNITED STATES PATENT OFFICE.

MAX GRAF, OF NEW YORK, N. Y.

COALHOLE-COVER.

1,312,395.

Specification of Letters Patent.

Patented Aug. 5, 1919.

Application filed January 23, 1919. Serial No. 272,669.

To all whom it may concern:

Be it known that I, MAX GRAF, a citizen of the United States, and a resident of the city of New York, borough of the Bronx, in 5 the county of Bronx and State of New York, have invented a new and Improved Coalhole-Cover, of which the following is a full, clear, and exact description.

This invention relates to coal hole constructions or the like and has particular reference to improved means for securing a coal hole cover to its base, with respect to a removable or detachable hinge construction for the renewal or interchange of covers and 15 also with respect to a key controlled automatically closing lock whereby the cover cannot be opened from the outside by any one not in authority or without a key.

While I show and describe my improvement applied to a side walk coal hole construction it is to be understood that certain features of the invention are adapted for use in other particulars, and consequently I do not wish to be unnecessarily restricted in 25 the scope of the claims.

With the foregoing and other objects in view the invention consists in the arrangement and combination of parts hereinafter described and claimed, and while the invention 30 is not restricted to the exact details of construction disclosed or suggested herein, still for the purpose of illustrating a practical embodiment thereof reference is had to the accompanying drawings, in which like reference characters designate the same 35 parts in the several views, and in which—

Figure 1 is an inside elevation of my improved coal hole cover open and with the base thereof in vertical transverse section.

40 Fig. 2 is a vertical sectional detail on the line 2—2 of Fig. 1.

Fig. 3 is a similar view on the same plane but with the cover locked closed.

Fig. 4 is a fragmentary plan view showing 45 the outside appearance of the hinge portion of my improvement, and

Fig. 5 is a detail view in elevation of one design of key for unlocking and opening the cover.

50 Referring now more specifically to the drawings I show a coal hole construction embodying a foundation 10 of concrete or the like having a chute or passageway 11 for the conveyance of coal or other objects, and 55 securely built in or otherwise fixed to the foundation 10 in a permanent manner in a

base member 12 shown in the form of an annular collar, though as to the particular form obviously I do not propose to be limited. Any other form than round might 60 be employed so far as my particular improvement is concerned. This base includes horizontal and vertical flange portions 12^a and 12^b respectively and a countersunk or rabbeted portion 12^c. The structure also 65 preferably includes a plurality of downwardly projecting anchor or leg members 13 having laterally projected feet 14 whereby the connection between the base and the foundation is made both secure and permanent. Obviously the base may be set in flush with the upper surface of the foundation or pavement and when once built in 70 place is understood to be a permanent fixture and not liable to become broken or 75 worn out.

The cover 15 is essentially circular or disk shaped as shown to correspond to the rabbeted seat 12^c into which it is fitted when closed, the upper surface of the cover lying 80 flush with the upper flange 12^a of the base, although preferably the central portion of the cover is convexed or crowned to increase its strength. The rear edge portion 85 of the cover is provided with a pivot bar 16 which lies and turns in a correspondingly formed groove or recess 17 formed in the base. This bar, however, lies substantially flush with the upper surface of the base and being without obstruction thereover is free, 90 except as otherwise stated below, to be lifted directly out of the groove 17. This bar obviously constitutes one of the principal features of the hinge around which the cover is adapted to be swung to open or 95 closed position.

18 indicates an auxiliary hinge member in the nature of a slide having a certain amount of radial movement along the under surface of the cover within a keeper 19 fixed 100 removably to a pair of spaced guides 20 by screws or the like 21. The slide 18 has a slot 22 along its longitudinal center and adjacent to its upper or outer end in which a stud 23 fixed to the cover 15 projects. At 105 the inner or lower end the slide is provided with a pair of knuckles 24 spaced on opposite sides of a butt 25 made as an integral portion of the base structure. The butt is provided with a horizontal slot 26 lying 110 between the knuckles 24, and a pivot pin 27 projects through the knuckles and said slot,

the pin being free for a certain amount of horizontal movement in the slot as will be noted in comparing Figs. 2 and 3.

The slide 18 has free slideable movement 5 in the keeper coincidentally with the pivotal movement of the cover around the axis 16 and to compensate for the eccentricities of the two pivots 16 and 27 the pin or pivot 27 moves outward along the slot 26 while the 10 cover is swung upward to open position. The upward or open swing of the cover is limited by several features: First by contact between the lug 23 and the upper end of the slot 22, the resistance of the butt 25 15 acting through the pivot pin 27 and also by the engagement between the pivot bar 16 and the wall of the groove 17. The cover, however, cannot be lifted from the base in any position so long as the slide 18 remains 20 attached as indicated. In order to remove the cover, however, after it is opened it is only necessary to remove the screws 21 setting free the keeper plate 19 and consequently releasing the cover from its hinge 25 connections.

The slide 18 carries a lug 28 located preferably centrally between the slot 22 and the knuckles, but not far below the lower end of the slot. While the hinge member 30 or slide 8 has rather loose sliding engagement in the keeper, the function of the lug 28 is to take up any looseness or lost motion vertically between the several portions of the hinge structure when the cover is closed, 35 said lug being drawn by the closing action of the cover snugly against the upper or inner surface of the keeper plate as shown in Fig. 3. This constitutes a wedging action and since the pivot pin 27 is held positively from upward movement by means of the butt 25 it follows that the slide 18 will be held in a substantially fixed position when closed. Therefore with the lug 28 acting as a wedge and bearing downwardly upon the keeper plate 45 19 fixed rigidly to the cover it follows that the hinge portion of the cover will be locked down snugly in its seat 12°.

Any suitable locking means may be provided remote from the hinge structure to 50 prevent the unauthorized opening of the cover on the outside. The locking means I prefer to employ, however, includes a bolt 29 slideable outward radially along the under surface of the cover and having a nose 30 55 engageable beneath the flange of the seat 12°. This bolt is confined substantially in the place indicated by any suitable keeper such as a pin 31 fixed in a pair of ears or lugs 32 and 32' attached on the under surface 60 of the cover. A weighted lever 33 is pivoted at 34 between the ear 32 and a corresponding ear 35. The lever and bolt both lie between the ears 32 and 35. The lever 33 is in the nature of a bell crank, the 65 shorter arm of which is slotted at 36 eccentric

trically of the pivot 34 and embraces a finger 37 projecting laterally from the bolt 29. When the cover is closed the weighted end of the lever 33 gravitating causes the outward projection of the bolt 29 and holds it 70 in such locking position. The cover is provided with a key hole 38 for the reception of a key 39, the key and hole being of individual mating character requiring that a particular key shall be used in each particular cover, but the bit portion 40 of the key in any event when the key is turned as shown in dotted lines in Fig. 1 will bear against a lug or finger 41 and so move the bolt bodily inward toward the center of the 80 cover thereby releasing the nose 30 from locking position. The finger 41 being an integral portion of the bolt is limited in its movement by striking against the ear 35 so that the operator knows when the bolt 85 is unlocked and while the key is in this position he will lift upon the handle portion thereof to open the cover.

When the cover is open it will stand unsupported in open position. To close the 90 cover the operator will either lower it by the use of the key as a handle while the key remains in the key hole, or he may slam the cover shut without danger of breakage because of the fact that it fits within the seat 95 of the base so perfectly, being guided in its closing movement by the compound hinge structure above set forth. If the cover is slammed shut the lock will automatically catch and hold it, the rounded portion of 100 the nose 30 wiping against the seat flange for this purpose.

I claim:

1. The combination of a base having a seat, a hinge slide, means pivotally connecting the slide to the base within the seat, a cover having a pivot bar coöperating with the upper portion of the base and with its axis parallel to the axis of the slide, and a keeper serving to confine the slide in close 110 parallel relation to the cover in all positions of the cover.

2. The combination of a fixed rigid base having a seat, a hinge slide, pivot means connecting the lower end of the slide to the base within the seat, a cover having pivotal connection with the base independent of the aforesaid pivot means and eccentric thereto, a keeper plate removably connected to the inner surface of the cover and holding 120 the slide adjacent to the cover for slideable movement coincidentally with the swinging movement of the cover, and means acting between the slide and the keeper plate serving to wedge the cover tight upon its seat 125 when closed.

3. In a coal hole cover construction, the combination of a base having an inward projection, a cover movable to closed position in contact with the base, a lock for the cover 130

- comprising a bolt carried by the inner surface of the cover and adapted to engage beneath said projection, and a key controlled gravity operated actuating means for said bolt, said bolt actuating means comprising a weighted bell crank having formed in one of its arms a slot eccentric to the pivot of the lever and having coöperation with a finger carried by the bolt.
- 10 4. In a coal hole structure, the combination of a base having a projection, a cover movable into closed position in contact with the base, a bolt movable along the inner surface of the cover to engage said projection in locking position, said bolt having on 15 its opposite sides a pair of rigid fingers, means to automatically slide the bolt to locking position when the cover is closed, said sliding means including a pivoted member having slotted connection with one of 20 said fingers, and a key projectable downward through the cover to release the bolt and serve as a handle for lifting the cover, said key coöperating with the other of said fingers.

MAX GRAF.
